HERMANN BOLLMANN, OF HAMBURG, GERMANY

METHOD OF BLEACHING FATTY OILS, MINERAL OILS, AND THE LIKE

Application filed December 16, 1925, Serial No. 75,743, and in the Netherlands November 18, 1925.

This invention relates to a method of and apparatus for bleaching fatty oils, mineral oils and the like by means of fuller's earth. In the bleaching of fatty oils and fats, mineral oils and the like by means of fuller's earth the method commonly heretofore employed is to add the quantity of fuller's earth which experiment has shown to be necessary to the oil and to cause this mixture to react while stirring and heating until the bleaching is effected. It has been proposed to make the process continuous by causing oil and fuller's earth impregnated with oil to pass through a suitable column in countercurrent or by conducting them in the same direction through a pipe of suitable length provided with an agitating device.

Experiments have now shown that the manner and proportions in which the oil and fuller's earth are allowed to contact are of primary importance not only with regard to the bleaching effectiveness of the fuller's earth but also with regard to the time required for the process.

The bleaching action depends on the high absorptive and adsorptive powers of the fuller's earth which has the property of retaining the colouring constituents of the oil. If a comparatively large quantity of fuller's earth is brought into contact with a comparatively small quantity of oil, the former immediately takes up the colouring constituents. In addition, however, the fuller's earth saturates itself with oil that has already been bleached, with the result that its absorptive powers towards the oil which is not yet bleached are diminished. Consequently a considerably larger quantity of fuller's earth and a longer period of action are necessary in the case when oil and fuller's earth are not mixed in the ratio requisite for the bleaching than would be necessary if the mixture is made in the first place in the correct proportions.

First experiment

It has been, for instance, found that soybean oil, mixed with 12% of fuller's earth and agitated while being heated in a vessel, re-

quired about two hours before the bleaching was completed.

On the other hand, it has been found that if the oil is first warmed and the fuller's earth then added in small quantities and in a heated state and brought into intimate contact with the oil or oil particles so that the addition of the fuller's earth is spread over the entire period of the treatment and the fresh fuller's earth has an opportunity of coming into contact with unbleached oil, then under otherwise equal experimental conditions it is possible to use 9% of fuller's earth only and moreover to effect bleaching to the same degree as in the first experiment in less than half an hour.

The conclusion to be drawn from this is, therefore, that the bleaching may be effected most quickly and effectively if oil and fuller's earth are, at the start, intimately mixed in the correct proportions.

Accordingly the method of this invention consists in causing fuller's earth and oil under treatment to come into intimate contact in small quantities at a time and in the requisite proportions for bleaching. The fuller's earth, preferably heated, say to about 100° C., is conveniently forced into contact with the oil by means of a current of air under pressure, while the oil, also preferably heated, say to about 100° C., is conveniently sprayed into a chamber where the bleaching is to be effected. Thus the finely divided hot fuller's earth contacts with the spray of preheated oil.

To carry out the method on a large scale a closed vessel, provided with a heating jacket and agitating device, is employed, the oil entering this from above and being distributed over the entire cross section of the vessel while the fresh fuller's earth is, at the same time, blown in by means of an air current and is mixed with the unbleached oil, while the latter is in the form of a spray, and in the proportion which corresponds to the quantity necessary for the bleaching of that part of the oil encountered. The percentage of fuller's earth, based on the amount of oil, varies according to the amount of color in the oil being treated. The size of the vessel may be such that the bleaching is completed by the

time the oil leaves the same. It is, however, possible to use a smaller vessel and to finish off the bleaching after effecting the mixing, in another vessel, after which oil and fuller's earth are separated in known manner, e. g. by filtration.

An apparatus for carrying out the method is illustrated diagrammatically and by way of example in the accompanying drawing.

10 The oil, previously warmed, is introduced through several nozzles 4 into the closed vessel 1 provided with a heating jacket 2 and an agitating device 3. The distribution of the oil is effected so that it takes place over the 15 entire cross section of the vessel 1. The fuller's earth is conveyed by means of the conveyor screw 5 rotating in a pipe 14, provided with a heating jacket 17, into the pipe 6, the wall of which is provided in its lower portion 20 with openings. The pipe 6 is perforated in its lower portion and is open at the bottom, and surrounded by the jacket 7. Air is blown into the jacket 7 by means of the pump 8 and passes through the openings in the pipe 6, 25 thence out through the open lower end of pipe 6 into the receptacle 1. The pump 8 withdraws air from the vessel 1 in order to avoid contacting the oil with excessive quantities of air. A gauze filter 16 prevents fuller's earth 30 entering the pump 8. The air entering vertical pipe 6 from the perforations, mixes with the falling powdered fuller's earth, and the mixture will be deflected by striking the upper flaring surface of the cone 9, to throw the 35 same outwardly over practically the entire surface of the receptacle 1. This action is assisted by the fact that the cone 9 is carried on a rotating rod 10. Much of the fuller's earth before striking the body of the oil, will 40 be struck by the sprays of hot oil from 4—4.

In the neighbourhood of the bottom of the vessel 1 an outlet pipe 11 is situated, which is connected with the pipe 12 which is closed at the top and is provided with agitating mechanism 15. The pipe 12 has a number of cocks 13 by means of which the contents of the vessel 1 may be removed. The oil still carrying some fuller's earth, drawn off from the cocks 13 is first of all tested to determine whether 45 the bleaching is complete and is then filtered or otherwise separated from the fuller's earth carried therein. The discharge flow is so regulated that the oil and fuller's earth have been 50 in contact for a sufficient time to enable an effective bleaching to take place.

I claim:—

1. A method of bleaching fatty oils, mineral oils and the like by means of fuller's earth, which consists in causing the fuller's earth and oil to come into intimate contact both in small quantities at a time both the oil and fuller's earth being in a finely subdivided state, whereby a minimum quantity of fuller's earth suffices for bleaching.

60 2. A method of bleaching fatty oils, min-

eral oils and the like by means of fuller's earth, which consists in blowing fuller's earth into contact with the oil in the form of a spray, while fresh portions of fuller's earth and fresh quantities of unbleached oil are continually contacting with each other.

70 3. A method of bleaching fatty oils, mineral oils and the like by means of fuller's earth as covered in claim 1, in which the fuller's earth and the oil are subjected to heating prior to contacting with each other.

75 4. A process of removing coloring matters from oil which comprises spraying preheated oil and directing a current of finely divided preheated bleaching earth, against the spray of preheated oil produced in the said first step and allowing contact of the said oil and fuller's earth while in a heated state, until said earth has sufficiently removed the coloring matter from the oil.

80 5. In the bleaching of oil by fuller's earth, the herein described step of directing a current of air carrying fuller's earth against a spray of oil, to mix the said fuller's earth and oil with each other.

85 In testimony whereof I affix my signature.
